(57) CLAIM

The ornamental design for a personal digital assistant holder, as shown and described.

DESCRIPTION

FIG. 1 is a left perspective view of a personal digital assistant holder showing my new design;

FIG. 2 is a right perspective view of the personal digital assistant holder shown in FIG. 1;

FIG. 3 is a front view of the personal digital assistant holder shown in FIG. 1;

FIG. 4 is a left side view of the personal digital assistant holder shown in FIG. 1;

FIG. 5 is right side view of the personal digital assistant holder shown in FIG. 1; and,

FIG. 6 is a bottom view of the personal digital assistant holder shown in FIG. 1.

The uneven broken lines immediately adjacent to the shaded area represent the bounds of the claimed design. The uneven broken lines within the shaded area represent attachment rivets and form no part of the claimed design. All other uneven broken lines represent the remaining portion of the personal digital assistant holder. The uneven broken line representations in FIGS. 1-6 are for illustrative purposes only and form no part of the claimed design.
